United States Patent Office.

NELSON O. TIFFANY, OF BUFFALO, NEW YORK.

Design No. 4,488, dated November 22, 1870.

DESIGN FOR A SCHOOL-DESK.

The Schedule referred to in these Letters Patent and making part of the same.

I, NELSON O. TIFFANY, of Buffalo, in the county of Erie and State of New York, have invented and produced a new and original Design for School-Desks, of which the following is a specification.

Nature and Objects of the Invention.

The first part of my invention relates to a superior form of bent wood end or standard for school-desks, possessing great strength and rigidity.

My invention further consists in a peculiar form for a brace or tie-plate for use, in connection with such wooden end, to strengthen it.

Also, in a suitable form for such brace-plate, and a seat-arm in one part.

Description of the Accompanying Drawing.

Figure 1 is an end view of a school-desk, with my design applied.

Figure 2 is a perspective view of one of the brace-plates and seat-arms of the same detached.

General Description.

A B represent bent wood legs, crossed at about mid-height, where they are gained together and united by a bolt of any form.

C represents a "top bracket," which may be of any suitable form.

The manner of arranging the upper ends of the legs A B on the bracket C, to which they are attached, forms no part of my invention. The said legs may be there united, both being made in one piece.

D represents a brace or tie-plate for strengthening the legs A B, being applied to them at their intersection, as shown in fig. 1, and d d perforations in the same, for the reception of screws e of any design.

F represents a seat-arm formed on or in one part with the brace-plate D.

f f represent perforated lugs on the seat-arm F, for the attachment of seat-slats. These form no essential part of the design.

The brace-plate D, either with or without the seat-arm F, may be made of either wood or metal.

The seat-arm being omitted, both edges of the brace-plate would be alike, in which case but one pattern would be required. With the seat-arms, a pair are simply opposites, as is also the case with the bent wood standards.

Claims.

I claim as my invention—

1. The shape or conformation of the bent wood ends or standards for school-desks A B, substantially as represented and described.
2. The form of the brace or tie-plate D d, substantially as represented and described.
3. The form of the brace or tie-plate D d, with seat-arm F, substantially as represented and described.

NELSON O. TIFFANY.
